UNITED STATES PATENT OFFICE.

CHARLES F. HENDERSON, OF MADISONVILLE, OHIO, ASSIGNOR TO THE KEMPER-THOMAS COMPANY, OF NORWOOD, OHIO, A CORPORATION OF NEW JERSEY.

WALL-BRACKET.

1,241,732.

Specification of Letters Patent.

Patented Oct. 2, 1917.

Application filed January 9, 1914. Serial No. 811,134.

To all whom it may concern:

Be it known that I, CHARLES F. HENDERSON, a citizen of the United States, and a resident of Madisonville, in the county of 5 Hamilton and State of Ohio, have invented certain new and useful Improvements in Wall-Brackets, of which the following is a full, clear, and exact description, reference being had to the accompanying drawings, 10 forming part of this specification.

It is the object of this invention to provide a knockdown wall bracket having a pocket which is of substantial, useful and yet of inexpensive structure. In the past, it has been 15 attempted, without any success, to mount wall pockets on cardboard for use in advertising. The brackets of this nature all used a hinge for securing a flap of cardboard to the base of such wall piece, so that in pack- 20 ing, the flap would close up. A flap of this kind could not be secured in a way to give any degree of permanency and it made too small a pocket to be of use. Moreover such a flap could not be bent to give more 25 capacity because then the means of attachment would be inadequate to support it in knock- down condition. Thus a valuable line of the advertising business has been practically closed from extensive use.

30 The special purpose of this invention is to provide a means for mounting a spacious pocket on a backing, and this is accomplished by that certain condition and arrangement of parts to be hereinafter specifically pointed out and claimed.

In the drawings,

Figure 1 is a perspective view of the bracket, set up.

Fig. 2 is a central vertical section thereof.

40 Fig. 3 is a perspective view of the bracket knocked down.

Fig. 4 is an enlarged view of one of the staples for securing the bracket arms to the backing.

45 In the preferred form of applying my invention, I provide a piece of cardboard or like material 1, designed to carry advertising matter; and on the lower end of this piece I mount the pocket and the bracket 50 arms to support it. The whole, when set up, may be hung on a wall by placing the aperture 2 over a nail or hook.

The bracket arms are preferably two in number and comprise vertical portions 3, 3, 55 to be secured to the board, and outwardly

and upwardly extending portions 4, 4, to hold the pocket. A head 5 is provided for each of the vertical portions, and a hooked end 6 for the pocket holding portion.

Staples formed with heads 7 and shanks 63 8, 8, are employed to secure the vertical portions to the board 1. Their shanks are inserted over these portions, and clenched at the back of the board to provide a loose mounting. The heads 5 then rest against the 65 top staple and the arms may be swung so as to lie flat on the board 1 (Fig. 3). This is the knockdown position.

The pocket is formed preferably of a curved piece of cardboard 9 of a segmental 70 cross section. This is provided with notches 10, 10, to seat over the bracket arms at the base of the board 1, and with apertures 11, 11, to engage the hooked ends 6, 6 of the said bracket piece. To mount the pocket, the 75 bracket arms are swung out from the knockdown position, the ends 6, 6, inserted in the apertures 11, 11, and the notches 10, 10, placed over the arms at the point where they leave the backing. 80

The pocket portion is, of course, shipped detached. Any flattening out of its segmental shape, which may occur in shipping, is of no disadvantage. The means of attachment holds the pocket at both sides so 85 that it is kept or forced as the case may be in its semi-cylindrical form.

The difference between this pocket as far as capacity and convenience is concerned, over the narrow V-shaped pocket formed by 90 a hinged flap, is very obvious. It will be observed that a good close fit of the lower edge of the pocket piece may be gained by a proper adjustment of size of bracket arms and pocket piece. These wall pockets or 95 brackets may be manufactured in large quantities at a small expense, without gluing of hinges or necessity of assembling the parts, and are therefore very valuable in the novelty advertising business. 100

Having thus described my invention, what I claim as new and desire to secure by Letters Patent, is:

1. In a device of the character described, a backing piece adapted to hang on a wall, a 105 plurality of supporting members having arms adapted to lie along the backing and return bend extensions, means for revolvably mounting the said members on the backing so that the extensions will swing away from 110

the board, a pocket forming piece and means for detachably mounting it on the extensions comprising devices to engage the pocket forming piece to hold the same in place.

5 2. A wall bracket comprising a board adapted to hang against a wall, a separate pocket forming piece formed in a curve shape and means for detachably mounting the pocket forming piece on the board, comprising members having a straight portion, and a return bend in the same plane to the straight portion, and means on the board for revolvably mounting the straight portion so that when the pocket forming piece is detached the return bend may be swung so as to lie along the board for shipment, said pocket forming piece having notches to engage over the straight portions of said members, when in operative position, hooks on the ends of the return bends and apertures in the pocket forming piece to engage said hooks.

10 3. A wall bracket comprising a board

adapted to hang against a wall, a separate pocket forming piece formed in a curve shape and means for detachably mounting the pocket forming piece on the board, comprising members having a straight portion, and a return bend in the same plane to the straight portion, and means on the board for revolvably mounting the straight portion so that when the pocket forming piece is detached the return bend may be swung so as to lie along the board for shipment, said pocket forming piece having notches to engage over the straight portions of said members, when in operative position, hooks on the ends of the return bends and apertures in the pocket forming piece to engage said hooks.

CHARLES F. HENDERSON.

Attest:

HARRY DETWILER,
JACOB SCHMIDT.
